US00D508394S

(12) **United States Design Patent** (10) Patent No.: **US D508,394 S**
Moffatt et al. (45) Date of Patent: **** Aug. 16, 2005**

(54) **MEMBER FOR STACKING WIRES OR CABLES**

(75) Inventors: **Wilbur Keith Moffatt**, Freeport, IL (US); **Kurt J. Fugman**, Rockford, IL (US)

(73) Assignee: **Greenlee Textron Inc.**, Rockford, IL (US)

(**) Term: **14 Years**

(21) Appl. No.: **29/211,674**

(22) Filed: **Aug. 19, 2004**

(51) LOC (8) Cl. **08-05**

(52) U.S. Cl. **D8/356; D8/395**

(57) **CLAIM**

The ornamental design for a member for stacking wires or cables, as shown and described.

DESCRIPTION

FIG. 1 is a perspective view of the member for stacking wires or cables according to our design;

FIG. 2 is a left side elevational view of the member for stacking wires or cables shown in FIG. 1;

FIG. 3 is a front elevational view of the member for stacking wires or cables shown in FIG. 1;

FIG. 4 is a right side elevational view of the member for stacking wires or cables shown in FIG. 1;

FIG. 5 is a top plan view of the member for stacking wires or cables shown in FIG. 1; and

FIG. 6 is a bottom plan view of the member for stacking wires or cables shown in FIG. 1.
